UNITED STATES PATENT OFFICE.

FRED S. ENGLISH, OF NEW LONDON, CONNECTICUT.

GRIPPER-TENSIONING MECHANISM FOR PRESSES.

Application filed May 6, 1925, Serial No. 28,354.

In the co-pending application of Thomas L. Perry and myself there is shown and described a gripper tensioning mechanism for presses and the object of the present invention is to secure the same or similar results to those secured through the mechanism described in said co-pending application, but through different instrumentalities.

The present invention relates to mechanism for holding the grippers upon the sheet and the same is adapted for use in printing presses as well as cutting and creasing presses. In present practice it is customary to provide a shaft which is carried by the impression cylinder of a press and on the shaft are mounted a series of curved members, commonly called grippers, which impinge against the forward edge of the sheet which is to be printed or cut and creased, pressing the edge of the sheet against the forward or leading edge of the impression portion of the cylinder. Generally, the grippers are closed on the sheet by spring action and they are opened by means of a cam through a lever action which turns the gripper shaft. When the grippers first act on the sheet the latter is stationary and the inertia of the sheet must be overcome practically instantly. This places a heavy burden upon the grippers when the sheet is first started, and requires much greater holding force than is afterwards necessary to carry the sheet around with the impression cylinder. If there is any slippage between the sheet and the grippers while the sheet is starting from the dead stop position, this will affect the register of the press. The object of the present invention is to provide means for placing an additional holding resistance upon the grippers while the inertia of the sheet is being overcome, and this holding action may be continued during any portion of the revolution of the cylinder, although in practice it has been found necessary to apply this additional pressure only during the starting of the sheet and for a short period thereafter. If the ordinary springs usually employed for closing the grippers upon the sheet are made sufficiently stiff to provide the extra pressure required during the starting of the sheet, there is difficulty in opening the grippers to deliver or take the sheet and the gripper operating mechanism in such case is subject to rapid wear. In the present case I have shown means separate from the ordinary means for

holding the grippers, which may place an additional or auxiliary pressure upon the grippers at the moment the latter are closed upon the sheet. Another object of my invention is to accomplish the above mentioned results with the fewest number of parts operating in a simple manner.

In the drawings forming part of this application,

Figure 1 is an end elevation of the cylinder of a printing press or cutting and creasing press, showing the usual mechanism employed for operating the grippers,

Figure 2 is an end elevation, on a larger scale, showing a portion of my improved device for applying auxiliary pressure to the grippers, and

Figure 3 is a front view of the same parts.

In the drawings 1 indicates the impression cylinder of the press and it is to be understood that this may be the impression cylinder of a printing press, a cutting and creasing press, or any other form of press, or it may constitute a transfer cylinder of a press, the invention being adaptable to any form of press in which grippers are used to take the sheet. I have also shown one end of the feed board 2 along which sheets are individually fed to the cylinder 1. There is mounted in the bearings 14 on the cylinder the ordinary gripper shaft 4 to which are secured the grippers 6 which engage the leading edge of the sheet and press against the leading edge of the impression portion of the cylinder 1. At the moment these grippers first engage the sheet the latter is at rest and momentarily the grippers must overcome the inertia of the sheet and must press on the same tightly for that purpose.

The ordinary device for rocking the shaft in order to close the grippers, consists of a crank 15 which is secured to the shaft 4 outside of the cylinder. On one end of this crank there is an anti-friction roller 5 which is acted upon by a cam 3 secured to a stationary portion of the frame of the machine. The roller 5 is held against the cam 3 by means of a compression spring 12 which surrounds the spring rod 11. One end of the spring presses against the spring step 13 while the other end acts against a collar on the rod 11 and the latter is pivoted at 9 to a segment 8 which rocks on a stud 10 fixed to a bracket 16 in the cylinder. The segment 8 has teeth which mesh with the teeth of a gear 7 secured to the gripper shaft 4.

The compression action of the spring 12 acting through the rod 11, segment 8, and the gear 7, serves to rotate the shaft 4, thereby pressing the roller 5 against the cam 3 and applying the force for closing the grippers 6 upon the sheet. The mechanism thus described comprises the usual parts employed for operating the grippers. To increase the pressure of the spring 12 to exert enough force on the grippers to hold the sheet when the latter first starts, causes undue wear and breakage, especially at the point where the roller 5 first engages the cam 3 at 17 and the present mechanism is intended to offer additional resistance to the grippers without increasing the strain on the parts at the time the grippers are being opened by the cam 3.

The mechanism for exerting this additional pressure is shown in Figures 2 and 3. Preferably on the end of the shaft 4 opposite to that on which the crank 15 is mounted, I attach the crank 18 in the form of a lever arm and it extends backward, or approximately in a reverse direction from the crank 15 so that when the free end of the crank 15 moves downwardly, the free end of the crank 18 moves upwardly, and vice versa. In the free end of the crank 18 there is an anti-friction roller 19 which is acted upon by a cam 20 which is secured to a stationary portion 21 of the press frame. There is a compression spring 22 which surrounds the spring rod 23 and one end of this spring 35 presses upon the crank 24 to rotate the shaft 4 in the direction necessary to close the grippers. The spring 22 serves to assist or reinforce the action of the spring 12 and it is part of the standard equipment now used on large cylinder presses. At the moment the grippers are closed by the mechanism shown in Figure 1 the roller 19 comes into contact with the cam 20 and this cam exerts a downward pressure upon the roller 45 so that the grippers 6 are held against the sheet with greater resistance than that caused by the joint action of the springs 12 and 22. After the sheet has been gripped and moved so that its inertia has been overcome the roller 19 will run off the cam 20 and the spring action of the springs 12 and 22 will exert sufficient pressure upon the grippers to hold the sheet during the remainder of the cycle of operation of the 55 press. By placing the auxiliary mechanism on the opposite end of the shaft 4 from the usual gripper closing mechanism the cam 20 may be inclined to force the roller 19 downwardly without breakage of the parts as there will be a slight torque in the shaft 4.

It is often necessary to open the grippers by swinging them entirely within the cylinder for convenience in make ready, at which time the roller 5 is entirely out of 65 the path of the cam 3. To do this the shaft

4 is rotated about 90 degrees, in which case the roller 19 will travel in an arc outside of or beyond the top of the cam 20 and if the press is started while the parts are in this condition no injury will be caused to the gripper mechanism while the grippers are in this retracted position. When the grippers are thrown back into the cylinder in this manner the teeth of the segment 8 run out of mesh with the gear 7 and the 75 spring crank 24 moves over beyond the dead center so that the spring 22 holds the grippers in the wide open position.

From the above it will be apparent that I have provided simple and efficient means for placing additional resistance upon the grippers momentarily at the time when the greatest pressure is required to overcome the inertia of the sheet. The active surface of the cam 20 may be prolonged if desired 85 but in most cases the auxiliary pressure will only be required for a brief period, after which it is released by the cam 20, so that by the time the grippers arrive at the point where they are opened by the cam 3 there 90 will be no greater strain on the opening mechanism than if the present auxiliary pressing device were not employed.

Having described my invention, what I claim is:

1. In a press the combination of a cylinder adapted to carry a sheet, a shaft, grippers thereon, a lever arm on said shaft and a stationary cam for operating said lever arm to press the grippers on the sheet at the moment the latter is taken and adapted to release said pressure immediately after the sheet has been taken.

2. In a press the combination of a cylinder adapted to carry a sheet, a shaft, grippers thereon for engaging and holding the sheet, lever arms on said shaft extending in opposite directions, spring means acting on one of said arms for closing the grippers on the sheet and means acting on the other of said arms for applying auxiliary holding force to said grippers and adapted to release the same before the grippers are opened.

3. In a press the combination of a cylinder adapted to carry a sheet, a shaft, grippers thereon for engaging and holding the sheet, lever arms on said shaft extending in opposite directions, spring means acting on one of said arms for closing the grippers 115 on the sheet, and a cam acting on the other of said arms for applying holding force to said grippers.

4. In a press the combination of a cylinder adapted to carry a sheet, a shaft, grippers thereon for engaging and holding the sheet, lever arms on said shaft extending in opposite directions, spring means acting on one of said arms to close the grippers 125 on the sheet and positive means acting on the sheet and positive means acting on the 130

other of said arms for holding the grippers in closed position.

5. In a press the combination of a cylinder adapted to carry a sheet, a shaft, grippers thereon adapted to engage and hold the sheet, a lever arm on said shaft having a roller, a stationary cam with which said roller is adapted to engage whereby said

cam will rock said shaft to hold the grippers upon the sheet, said roller being adapted to travel free of said cam when the grippers are turned inside the cylinder. 10

Signed at the city of New London, county of New London and State of Connecticut, this 1st day of May, 1925.
